SHAVING KIT

Onofrio J. Natale, San Francisco, Calif.

Application January 21, 1953, Serial No. 23,229

Term of patent 14 years

(Cl. D86—10)

To all whom it may concern:

Be it known that I, Onofrio J. Natale, a citizen of the United States, residing at San Francisco, county of San Francisco, State of California, have invented a new, original, and ornamental Design for a Shaving Kit, of which the following is a specification, reference being had to the accompanying drawing, forming a part hereof, wherein:

Fig. 1 is a front perspective view of a shaving kit, showing my new design;

Fig. 2 is a top plan view of the shaving kit shown in Fig. 1;

Fig. 3 is a sectional view thereof taken along the line 3—3 in Fig. 2;

Fig. 4 is a side elevational view; and

Fig. 5 is a rear elevational view thereof as it appears with the shaving brush, soap stick, razor and blade container partly withdrawn.

The disclosure of the shaving brush, soap stick, razor and blade container shown in dotted lines on the drawing is merely for the purpose of illustration.

I claim:

The ornamental design for a shaving kit, substantially as shown and described.
